CLAIM

The ornamental design for a payment card with a notch, as shown and described.

DESCRIPTION

FIG. 1 is a first side perspective view of a first embodiment of a payment card with a notch showing our new design;

FIG. 2 is a first side view thereof;

FIG. 3 is a top elevational view thereof;

FIG. 4 is a bottom elevational view thereof;

FIG. 5 is a second side view thereof;

FIG. 6 is a left side elevational view thereof;

FIG. 7 is a right side elevational view thereof;

FIG. 8 is an enlarged view of design features comprised within a circle 8 in FIG. 1;

FIG. 9 is first side perspective view of a second embodiment of a payment card with a notch showing our new design;

FIG. 10 is a first side view thereof;

FIG. 11 is a top elevational view thereof;

FIG. 12 is a bottom elevational view thereof;

FIG. 13 is a second side view thereof;

FIG. 14 is a left side elevational view thereof;

FIG. 15 is a right side elevational view thereof; and,

FIG. 16 is an enlarged view of design features comprised within a circle 16 in FIG. 9.

The dashed lines show portions of a payment card edge. The dashed lines are illustrative only and form no part of the claimed design. The dashed-dot-dashed lines in FIGS. 1, 8, 9, and 16 show a boundary of the enlarged portion of the design features of the payment card with a notch.
